(57) **CLAIM**

The ornamental design for a jacketed load cell, as shown and
described.

DESCRIPTION

FIG. 1 is a perspective view of a load cell with cover;
FIG. 2 is a front side view of the load cell with cover;
FIG. 3 is a bottom side view of the load cell with cover;
FIG. 4 is a left side view of the load cell with cover;
FIG. 5 is a right side view of the load cell with cover;
FIG. 6 is a bottom edge view of the load cell with cover; and,
FIG. 7 is a top edge view of the load cell with cover.
